UNITED STATES PATENT OFFICE.

JOHN G. LEWIS, OF ST. LOUIS, MISSOURI, ASSIGNOR TO LEWIS BLIND STITCH MACHINE COMPANY, OF ST. LOUIS, MISSOURI, A CORPORATION OF MISSOURI.

SEAM FOR SEWED ARTICLES.

No. 830,481.

Specification of Letters Patent.

Patented Sept. 4, 1906.

Application filed February 16, 1899. Renewed July 27, 1901. Serial No. 69,990.

To all whom it may concern:

Be it known that I, JOHN G. LEWIS, a citizen of the United States, residing at the city of St. Louis, in the State of Missouri, have invented a certain new and useful Hem or Seam for Sewed Articles, of which the following is such a full, clear, and exact description as will enable any one skilled in the art to which it appertains to make and use the same, reference being had to the accompanying drawings, forming part of this specification.

The object of my invention is to make a hem or seam for sewed articles which will be neat in appearance and durable.

My invention consists in a hem or seam for sewed articles, in which a portion of the material is folded upon itself and the folded portion secured to the main part of the material by blindstitches piercing said material in the direction of the length of the hem, and in other novel features which are described in the following specification and pointed out in the claims affixed hereto.

In the accompanying drawings, which illustrate a hem made in accordance with my invention, Figure 1 is a front view. Fig. 2 is a transverse section. Figs. 3 and 4 are sectional views showing the manner of forming the hem or seam, and Fig 5 is an enlarged view showing the form of stitch.

Like marks of reference refer to similar parts in the several views of the drawings.

10 is the main layer of the material. In the form of hem shown, a portion 11 is folded back upon the layer 10. This portion 11, however, may be a separate piece of material in some cases. The edge 12 of the portion 11 is preferably turned under, as best shown in Fig. 2, so that there will be no raw edge exposed in the completed hem or seam. The layers of cloth are then bent around a guide or finger 13 and the stitches passed through the same in the direction of the length of the hem or seam. The stitches pass down alternately at each side of the edge of the hem or seam. At that side of the edge of the seam beyond which the main layer 10 projects the needle passes down through said layer 10, as shown by the dotted line A of Fig. 3. In some instances the needle in passing down at the other side of the edge of the seam may pass through the layers 11 and 12 and into the main layer 10. In most cases, however,

I prefer to have the needle either pass into the outer layer 11 only, as shown in dotted line B of Fig. 4, or through the layer 11 into the layer 12, as shown in dotted line C in said figure. In either of the latter cases the layer 10 will not be drawn or puckered upon the side where the stitches do not show, as would be the case, especially in thin goods, if the needle penetrated into the layer 10. In the form of hem or seam shown, two threads are used to form the stitches, 14 being the upper and 15 the lower thread.

I am aware that hems have previously been made in which the folded portion of the material was held to the main part of the material by blindstitches piercing the goods in a direction at right angles to the length of the hem, and I do not claim the same.

Having fully described my invention, what I claim as new, and desire to secure by Letters Patent of the United States, is—

1. A hem or seam for sewed articles, consisting of a main layer of textile or similar material, and one or more superimposed layers of material secured to said main layer by two connected rows of stitches passed into the material in the direction of the length of the hem or seam, one of said rows of stitches being at each side of the edge of said superimposed layer or layers, said stitches entering into and emerging from the same surface and being locked or enchain'd and substantially concealed from view on the opposite surface.

2. A hem or seam for sewed articles, consisting of a main layer of textile or similar material, and one or more superimposed layers of material secured to said main layer by two connected rows of stitches passed into the material in the direction of the length of the hem or seam, one of said rows of stitches being at each side of the edge of said superimposed layer or layers, said stitches entering into and emerging from the same surface and being composed of a needle-thread and a bobbin-thread locked or enchain'd and substantially concealed from view on the opposite surface.

3. A hem or seam for sewed articles, consisting of a main layer of textile or similar material, and one or more superimposed layers of material secured to said main layer by two connected rows of blindstitches passed into the material in the direction of the length of the hem or seam, one of said rows of stitches

- entering the main layer of material and the other entering one or more of said superimposed layers but not the main layer, whereby drawing of the main layer is prevented.
4. A hem or seam for sewed articles consisting of a main layer of textile or similar material and one or more superimposed layers of material secured to said main layer by two connected rows of stitches, one of said rows of stitches entering the main layer of the material and the other entering one or more of the superimposed layers but not the main layer, said stitches entering and emerging from the same surface and being locked or enchainued and substantially concealed from view on the opposite surface.
5. A hem or seam for sewed articles, consisting of a main layer of textile or similar material, and one or more superimposed layers of material secured to said main layer by two connected rows of stitches passed into the material in the direction of the length of the hem or seam, one of said rows of stitches entering the main layer of material and the other entering one or more of said superimposed layers but not the main layer, said 40 stitches entering into and emerging from the same surface and being composed of a needle-thread and a bobbin-thread locked or enchainued and substantially concealed from view on the opposite surface.
6. A hem or seam for sewed articles, consisting of a main layer of textile or similar material and one or more superimposed layers of material secured to said main layer by two connected rows of stitches passed into the material parallel with and at opposite sides of the fold 12, interlocked within the material and having their exposed threads crossed on the line of the fold 12, but exterior thereto.
7. A hem or seam for sewed articles, consisting of a main layer of material folded upon itself to form the hem, the outer edge of said folded portion being itself folded under, as at 12, two rows of blindstitches comprising upper and lower threads passed into the material parallel with and at opposite sides of the fold 12, interlocked within the material and having their exposed threads crossed on the line of the fold 12, but exterior thereto.

In testimony whereof I have hereunto set my hand and seal in the presence of the two subscribing witnesses.
